United States Patent Office

Des. 192,578
Patented Apr. 10, 1962

192,578

ACCORDION

Nicholas T. Argiro, 780 Riverside Drive, New York, N.Y.

Filed Mar. 14, 1961, Ser. No. 64,283

Term of patent 7 years

(Cl. D56—1)

FIG. 1

FIG. 2

FIG. 1 is an elevational view of an accordion showing my new design; and

FIG. 2 is a top plan view thereof.

The bottom of the accordion is the same in appearance as the top.

I claim:

The ornamental design for an accordion, as shown and described.
